DESIGN FOR A NECKLACE

Harry Sheer, Brooklyn, N. Y.

Application November 1, 1945, Serial No. 123,385

Term of patent 7 years

(Cl. D45—16)

To all whom it may concern:

Be it known that I, Harry Sheer, a citizen of the United States, residing at Brooklyn, in the county of Kings, city and State of New York, have invented a new, original, and ornamental Design for a Necklace, of which the following is a specification, reference being had to the accompanying drawing, forming part thereof.

In the drawing:

Fig. 1 is a front elevational view of a necklace showing my new design;

Fig. 2 is a side elevation thereof;

Fig. 3 is an elevational view of a portion of the necklace looking in the direction of the arrows 3—3 of Fig. 1; and

Fig. 4 is a sectional view on the line 4—4 of Fig. 3.

I claim:

The ornamental design for a necklace, substantially as shown.

HARRY SHEER.
